UNITED STATES PATENT OFFICE.

MONTROSE P. McARDLE, OF WEBSTER GROVES, MISSOURI, ASSIGNOR TO HYDRAULIC PRESS BRICK COMPANY, OF ST. LOUIS, MISSOURI, A CORPORATION OF MISSOURI.

SCUM GUTTER.

Application filed October 31, 1925. Serial No. 66,004.

This invention relates to scum gutters, and has more particular reference to a structure especially applicable to swimming pools and the like, although it is capable of use generally where it is sought to remove, by surface drainage, from a liquid, foam, scum, and other floating material. Certain features of the invention, also, are capable of wide application to gutters generally.

10 An object of the invention is to provide an improved form of gutter which may be simply constructed in transverse section of only two sections or blocks.

15 Another object is to provide an improved corner structure adapted to compensate for expansion in the walls of the pool.

20 A further object is the provision of an improved manner of connecting the drain to the gutter so that construction of the pool is expedited by its use.

25 Other objects of the invention, some of which are more or less incidental or ancillary to the foregoing, will appear in the course of the following description.

30 In the accompanying drawings forming part of this specification, in which like numbers of reference denotes like parts wherever they occur,

35 Figure 1 is a fragmentary elevational view of the inside of a swimming pool embodying this invention, partly in section on the line 1—1 in Figure 2;

40 Figure 2 is a fragmentary horizontal sectional view taken on the line 2—2 in Figure 1;

45 Figure 3 is a fragmentary horizontal sectional view taken on the line 3—3 in Figure 1, the concrete outer shell or filling being omitted to afford a clearer view of the masonry;

50 Figure 4 is a fragmentary plan view showing the manner of forming a lateral recess and external corners in the walls of the pool;

55 Figures 5 and 6 are views similar to Figure 4 and depicting other forms of external and internal corners;

60 Figure 7 is an enlarged fragmentary transverse vertical sectional view through a wall exhibiting the detailed connection of the gutter to one form of drain;

65 Figure 8 is a sectional view similar to that of Figure 2, but showing another form of drain connection to the gutter;

Figure 9 is an enlarged fragmentary 55 transverse vertical sectional view taken on the line 9—9 in Figure 8;

70 Figure 10 is a vertical longitudinal sectional view taken on the line 10—10 in Figure 8; and

75 Figure 11 is a plan view of a modified form of gutter block adapted for connection to the type of drain depicted in Figures 8, 9, and 10.

80 The structure illustrated in Figures 1, 2, 3, and 7 comprises a course of gutter blocks 1, laid on the underlying courses of stretchers 2 commonly used in forming the walls 3 of a swimming pool. The said blocks have flat bottoms 4, and flat rear and front faces 5 and 6, respectively. A preferably concave-bottomed gutter 7 is formed in the blocks 1 intermediary of the upwardly projecting front and rear flanges 8 and 9, respectively. The flanges 8 have rounded tops 10, and the flanges 9 have flat tops 11 disposed on a higher level than the tops 10.

85 A course of corbel blocks 12 is laid on the course of gutter blocks 1, the flat bottom face 13 of the corbel blocks meeting the top face 11 of the gutter blocks 1, and the front face 14 of the corbel blocks being forwardly and upwardly inclined, being preferably concave at its lower portion to form a continuous and unbroken surface with the rear gutter face 15 of the gutter blocks 1, and convex at its upper portion so that the upper portion terminates as a vertical continuation of the front faces 16 of the blocks superposed on the corbel blocks 12. The faces 16 are

90 preferably disposed in retracted relation to the faces 6, so that the flange 8 is made more readily accessible as a life rail, and so that water from the curb 17 does not flow back into the pool, but drains into the gutter 7. The rear end 18 of the corbel blocks projects beyond the rear face 5 of the gutter blocks 1 in order to balance the weight of the front portion overhanging the gutter blocks.

95 The curb 17 is preferably formed of suitable non-skid material, such as roughened tile and the like, and may be disposed at any suitable height above the gutter 11 by the interposition of appropriate brickwork and the like between the curb 17 and the corbel blocks 12. In the present instance, the brickwork consists of a lower course of flatters 19, an intermediate course of headers

and stretchers 20, and an upper course of flatters 21, which may bear suitable distance markers.

The blocks 1 are laid so that the bottom 5 of the gutter 7 and the top 10 of the life rail or flange 8 are level, and drain pipes 22 are connected to the gutter at suitable intervals, preferably of about ten feet. For this purpose, some of the blocks 9 are formed with 10 a central cylindrical opening 23 extending through their bottom walls or webs 24, the said openings enlarging laterally all around at their upper and lower ends to form retracted shoulders 25 and 26, respectively, 15 best shown in Figure 7. A sleeve 27 fits in the opening 23 and is internally screw-threaded to fit an exteriorly screw-threaded inner sleeve 28, the inner sleeve 28 having a flange 29 which bears on the upper 20 shoulder 25 and the outer sleeve 27 having a flange 30 which bears on the lower shoulder 26. The piping 22, preferably lead, passes through the inner sleeve 28, and flares outwardly at its upper end to form a flange 31 25 that is clamped between the flange 29 and a ring 32 secured to the flange 29 preferably by means of suitable screws. A drain sieve 33, preferably of the inverted cup or beehive type, fits within the ring 32.

30 Instead of the beehive form of drain shown in Figures 1, 2, and 7, a form of drain shown in Figures 8, 9, and 10 may be used. The said drain comprises a substantially pyramidal receptacle or box 34, having 35 a grate 35 secured to the open top thereof in any suitable manner and so that it preferably lies flush with the bottom of the gutter 7. The lower end of the box develops into an annular neck 36, externally threaded 40 to receive a flanged clamping ring 37, co-operating with flanged pipe section 38 to secure the said pipe thereto. Pipe section 38 is secured to elbow pipe section 39 through union 40 threading thereon. Pipe 38 is first 45 roughly located in place and the concrete portion of the wall poured around the same. Pipe section 38 is preferably of lead so that it may be easily manipulated to finally locate the box 34 more exactly in its appropriate position, the vertical adjustments being effected by changing the length of the pipe 38 and, also, by using packing 41 of suitable thickness in the unions 37 and 40. Special gutter blocks 42 are formed with 50 recesses 43 in one end to accommodate the drain boxes 34. The recesses preferably enlarge laterally at their upper ends to form depressed seating faces 44 for the flanged upper end of the boxes. The blocks 42 are formed 55 right and left, and are placed together end to end so as to inclose the box 34 after the latter has been fixed in place. The other blocks 1 of the gutter are then laid in the course.

60 65 It will be observed in Figure 2 that the

corner gutter blocks 45 are formed right and left and are joined at end faces 46 arranged convergingly toward the internal corner of the meeting walls with respect to the transverse other end faces 47 of the said blocks 45, preferably at an angle of forty-five degrees thereto. The end faces 48 of the corbel blocks 12 are staggered with relation to the end faces 47 of the gutter blocks 1, as best shown in Figure 3. Those blocks 12 nearest 70 the corner have oblique end faces 49 adapted to fit the converging end faces 50 of a special corner block 51 interposed therebetween. The faces 49 and 50 are in staggered relation with respect to the faces 46 and 47 of 75 the gutter blocks. This arrangement of oblique faces enables the blocks to shift slightly with relation to one another parallel to the said oblique faces, and so compensate for any undue or unequal expansion of the walls 80 resulting from changes in temperature or other causes.

Figure 4 illustrates special corbel blocks 52 and gutter blocks 53 for forming the external corners 54 of walls having recesses 55 85 therein. Figures 5 and 6 depict other forms of external corner blocks for recesses of different depths.

The gutter and corbel blocks may be formed of any suitable material, but plastic 90 clay is preferable. The blocks and the brick lining of the pool are preferably enameled on their exposed faces.

Having thus fully described this invention, I hereby reserve the benefit of all 100 changes in form, arrangement, order, or use of parts, as it is evident that many minor changes may be made therein without departing from the spirit of this invention or the scope of the following claims.

105 I claim:

1. In a structure of the class described, the combination of a block having front and rear upwardly projecting flanges to form an intermediate gutter; and a second block having its bottom face supported on the top face of the rear flange, and having a front portion overhanging the said gutter and forming a continuation of the rear face of said gutter, the rear portion thereof projecting beyond the rear face of the flanged block to balance the weight of the overhanging front portion.

2. In a structure of the class described, the combination of a block having a groove 110 defined by flanges, and a second block having its front face forming a continuation of said groove and having its rear portion projecting beyond the rear face of the inner flange of said first-named block.

3. In a structure of the class described, the combination of a block presenting upwardly directed flanges to form a gutter and a second block disposed on the rear flange 115 of the first-named block, the front face there-

of forming a continuation, said gutter and the rear portion of said second-named block projecting beyond the rear face of said rear flange.

5. In a structure of the class described, the combination of a block presenting upwardly directed flanges to form a gutter, and a second block disposed on the rear flange of the first-named block, the front face thereof

forming a continuation of said gutter and terminating inwardly of the front face of the inner flange of said first-named block, the rear portion of the second-named block projecting beyond the rear face of the rear flange of said first-named block. 15

In testimony whereof I hereunto affix my signature.

MONTROSE P. McARDLE.
